UNITED STATES PATENT OFFICE.

CHARLES G. SMITH, OF MEDFORD, MASSACHUSETTS, ASSIGNOR, BY MESNE ASSIGNMENTS, TO RAYTHEON MANUFACTURING COMPANY, OF CAMBRIDGE, MASSACHUSETTS, A CORPORATION OF MASSACHUSETTS.

ELECTRICAL APPARATUS AND METHOD.

Application filed April 25, 1921, Serial No. 464,358. Renewed November 22, 1926.

The present invention relates to electrical apparatus and more particularly to apparatus of the type disclosed in the co-pending applications of Smith Serial No. 415,536, filed October 8, 1920, and Serial No. 418,263, filed October 20, 1920.

The mean free path of an electron in a gas, as herein meant, is the average distance which an electron travels under the influence of an electric field impressed on the gas before ionizing impact with a gas molecule (or atom). If the potential difference through which the electron passes is sufficiently great to bring the electron up to ionizing speed before impact, ionization will take place, the collision in this case resulting in more electrons and positive ions being given off from the gas molecule, the positive ions passing to the cathode and releasing further electrons this process being cumulative and sustaining gaseous conduction. The electrical conduction through the gas increases with its pressure and the mean free path of an electron becomes progressively shorter with increases in pressure.

It is the object of the present invention to improve tubes of the character described in such a manner that the potential drop through the tube may be reduced, the permissible gas pressure increased, and other advantages obtained.

With this object in view it is found that by the employment of an inert monatomic gas within the tube, such as helium, neon or argon, the potential drop through the tube may be substantially reduced and the allowable gas pressure increased. The use of an inert monatomic gas such as helium is exceedingly important as in the first place the electrons in these gases have a mean free path which is so long that a helium filled tube may be successfully operated at a pressure many times as great as the permissible pressure if air or a similar gas were employed. In addition the use of helium and similar inert gases is important as these gases do not react chemically with the materials of the tube and cause changes in gas pressure.

A further feature of the present invention consists in the use of an absorbent material such as gas-mask charcoal in communication with the helium or other gas to absorb and

extract impurities in the form of active gases which may be initially mixed with the inert gas. This absorbent material to a lesser extent absorbs a certain amount of the inert gas and owing to the fact that it contains this residual volume of helium or other inert gas is enabled to give out this gas and equalize the pressure in the event that some helium may eventually be absorbed by the electrodes during the operation of the tube. In the simplest embodiment of the invention which has yet been devised the charcoal is located directly in the tube itself where it absorbs impurities from the helium during the filling of the tube and is thereafter in readiness during the operation of the tube to stabilize the pressure to a certain extent.

In the accompanying drawings illustrating the preferred form of the invention Fig. 1 represents an elevation partly in section of a tube embodying the principles of the invention; Fig. 2 is a sectional elevation of the electrodes; and Fig. 3 is a diagram illustrating the form of circuit in which the tube is embodied as a rectifier.

Referring to the illustrated embodiment of the invention a gas filled receptacle 10 receives cooperating electrode members 12 and 14 which are in the form of concentric cylinders supported at opposite ends of the receptacle 10. The inner electrode cylinder 12 has a reduced portion 16 extending within a cooperating cylinder and a larger portion 18 of approximately the diameter of the outer cylinder, this portion of larger diameter being connected with supporting members 20 which are in turn connected with a base member 22 at one end of the receptacle. The outer cylinder 14 is supported from the opposite end of the receptacle through supporting wires 24 which emerge from a base member 26 projecting from the end of the receptacle. The electrode cylinders are connected with leads 30 and 31 respectively, the two leads extending from opposite ends of the tube 10. A magnetic field is introduced in the space separating the two cylinders and is localized through the provision of iron or steel tubes 32 and 33 received within the outer electrode cylinder 14, as indicated in Fig. 2, and separated at their inner ends in order to localize the magnetic field in a manner which will

be obvious to those skilled in the art. The magnetic field may be conveniently created by a permanent magnet indicated at 36.

This tube is filled with helium or a similar inert monatomic gas which may be at a pressure of approximately one-half a centimeter which, as stated previously, is many times the pressure which may be employed with air or with active gases such as oxygen, 5 nitrogen and hydrogen. This permissible high pressure simplifies the filling of the tube and in addition has the distinct advantage that if a small absolute amount of helium or other gas condenses upon the walls 10 of the tube or is absorbed by the electrode the change in the relative pressure of the gas is very small as compared with the change which would result if a substantially lower pressure were employed. One end of 15 the receptacle contains gas-mask charcoal 40 which may be retained in place by glass wool, indicated at 42. This charcoal readily absorbs the active gases which may be contained in the monatomic gas as an impurity 20 but only feebly absorbs the pure inert gas, enabling the tube to be absolutely freed from everything except the inert gas. The employment of this charcoal is not only 25 advantageous in initially freeing the helium from impurities but, in addition, acts as a reservoir to absorb any active gases which 30 may be evolved from the electrodes during the operation of the tube.

Fig. 3 illustrates a simple form of circuit 35 embodying the tube as a rectifier and comprising an input circuit, indicated at 44, capable of delivering alternating current to the primary of a step-up transformer 46, the secondary of which is embodied in an output 40 circuit containing the tube, which rectifies the high voltage alternating current delivered thereto. This output circuit may be connected with any desired form of load circuit (not shown) to utilize the high voltage 45 current so rectified.

While it has been proposed to lower the voltage drop in discharge tubes by using inert gas, I believe I am the first to discover that, in short-path tubes embodying the 50 mean free path principle as disclosed herein, and in my aforesaid applications, the spacing of the electrodes or the gas pressure between the electrodes may be greatly increased by means of certain gases in which the mean free path of electrons is exceptionally long. While I consider helium the best gas for this new purpose other gases 55 have the requisite characteristics, chief of which are that their molecules have high impact elasticity (i. e. that property whereby a large fraction of impacts with electrons moving at ionizing velocity are elastic and non-ionizing) or their molecules are small 60 so as to be impacted less frequently by electrons traveling in the space,

As more fully described in my copending applications, the outer electrode 14 constitutes a hollow cathode from which electrons may travel, when 14 has negative polarity, along paths which are longer than the shortest 70 distance between the electrodes, thereby causing ionization which permits gaseous conduction between the electrodes during each half-cycle when 14 is negative.

I have found that in the operation of this 75 invention the monatomic gas, at a pressure of the order of that above mentioned, prevents "clean-up", that is prevents the gas pressure from decreasing during operation. This I believe to be due to adhesion to the 80 cathode surface of a layer of the gas sufficiently thick to protect the surface from ion bombardment so that gas molecules are not permanently entrapped in the cathode surface during operation. This function of the 85 gas is of course peculiar to non-thermionic tubes in which the cathode functions below the temperature at which the operation is dependent upon thermionic emission from the cathode since in thermionic tubes employing incandescent filaments or "hot spots" the cathode is not subjected to ion bombardment of sufficient velocity to cause "clean-up" and an incandescent cathode will 90 not permanently retain gas. 95

The terms "bi-lateral conduction between the electrodes" of course means conduction in both directions across the gas gap and "unilateral conduction" means conduction substantially in one direction only. 100

I claim:

1. Electrical apparatus of the type having electrodes with a gas space therebetween which is restricted in length substantially to the mean free path of electrons therein for 105 restricting gaseous conduction between the electrodes, characterized by means for increasing the permissible length of said space over the length in air at the same pressure for a corresponding degree of restriction of gaseous conduction, said means comprising monatomic gas in said space. 110

2. Electrical apparatus of the type having electrodes with a gas space therebetween which is restricted in length substantially to the mean free path of electrons therein for restricting gaseous conduction between the electrodes, characterized by means for increasing the permissible length of said space over the length in air at the same pressure for a corresponding degree of restriction of gaseous conduction, said means comprising monatomic gas in said space, and means comprising differently shaped electrode surfaces permitting gaseous conduction between the electrodes in one direction. 115

3. Electrical apparatus of the type having electrodes with a gas space therebetween which is restricted in length substantially to the mean free path of electrons therein 120

for restricting gaseous conduction between the electrodes, characterized by means for increasing the permissible length of said space over the length in air at the same pressure for a corresponding degree of restriction of gaseous conduction, said means comprising helium in said space.

4. Electrical apparatus of the type having electrodes with a gas space therebetween which is restricted in length substantially to the mean free path of electrons therein for restricting gaseous conduction between the electrodes, characterized by means for increasing the permissible length of said space over the length in air at the same pressure for a corresponding degree of restriction of gaseous conduction, said means comprising helium in said space, and means comprising differently shaped electrode surfaces permitting gaseous conduction between the electrodes in one direction while restraining conduction in the opposite direction.

5. Electrical apparatus comprising electrodes with a gas space therebetween which is comparable in length to the mean free path of electrons therein for resisting gaseous conduction between the electrodes, and means for increasing the permissible gas pressure in said space over that pressure of air, in a space of the same length, which affords corresponding restriction of gaseous conduction, said means comprising monatomic gas molecules substantially to the exclusion of air molecules.

35 6. Electrical apparatus comprising electrodes with a gas space therebetween which is comparable in length to the mean free path of electrons therein for restricting gaseous conduction between the electrodes, means for increasing the permissible gas pressure in said space over that pressure of air, in a space of the same length, which affords corresponding restriction of gaseous conduction, said means comprising monatomic gas molecules substantially to the exclusion of air molecules, and means permitting gaseous conduction between the electrodes in one direction without preventing substantial conduction in the opposite direction.

50 7. Electrical discharge apparatus of the type requiring gas in the space between the electrodes for conduction therebetween under normal conditions of operation, means for restricting conduction between the electrodes in one direction comprising an arrangement of the electrodes such that the gas space therebetween is comparable in length to the mean free path of electrons in the gas, and means for increasing the permissible gas pressure in said space over that pressure of air, in a space of the same length, which affords corresponding restriction of gaseous conduction, said last means comprising monatomic gas in said space.

8. Electrical discharge apparatus of the type requiring gas in the space between the electrodes for conduction therebetween under normal conditions of operation, means for restricting conduction between the electrodes in one direction comprising an arrangement of the electrodes such that the gas space therebetween is comparable in length to the mean free path of electrons in the gas, means for increasing the permissible gas pressure in said space over that pressure of air, in a space of the same length, which affords corresponding restriction of gaseous conduction, said last means comprising monatomic gas in said space, and means whereby electrons leaving one electrode are caused to travel in paths longer than the shortest distance between the electrodes, thereby causing ionization which permits conduction in one direction.

9. An electrical apparatus comprising electrodes immersed in an inert monatomic gas and having surfaces spaced apart a distance comparable to the mean free path of electrons in the gas and arranged for gaseous conduction from one electrode to the other under conditions which restrain conduction in the opposite direction, the inert monatomic gas serving to increase the permissible spacing between said surfaces.

10. An electrical apparatus comprising electrodes immersed in an inert monatomic gas and having opposing surfaces spaced apart a distance which is short and comparable to the mean free path of electrons in the gas, means for creating an electric field between the electrodes, and means for lengthening the paths of electrons impelled by the electric field to distances which are sufficiently long to initiate conduction, the inert monatomic gas serving to increase the permissible spacing between said surfaces.

11. An electrical apparatus, comprising a hermetically sealed tube filled with an inert monatomic gas at a pressure of the order of magnitude of one-half a centimeter, electrodes immersed in the gas within the tube and so designed and located with respect to one another that all direct paths available for gaseous conduction between the electrodes are of the order of magnitude of the mean free path of the electrons, and means for creating an electric field between the electrodes.

12. An electrical apparatus comprising a sealed tube containing gas at a predetermined pressure, electrodes having surfaces spaced a distance comparable to the mean free path of electrons in the gas at said pressure, and means within the sealed tube for automatically compensating for gas absorption due to operation of the tube, whereby the mean free path of the electrons is maintained approximately constant.

13. An electrical apparatus comprising a

sealed tube containing gas at a predetermined pressure, electrodes having surfaces spaced a distance comparable to the mean free path of electrons in the gas at said pressure, and porous material having absorbed therein a quantity of gas sufficient to compensate for gas absorption due to normal operation of the tube for a long period of time, whereby the mean free path 10 of the electrons is maintained approximately constant.

14. A rectifier comprising a cathode and an anode with a gas space therebetween comparable in length to the mean free path 15 of electrons in the gas for restricting gaseous conduction therebetween, means for increasing the permissible spacing of the electrodes comprising monatomic gas in said space, and means comprising differently shaped electrode surfaces permitting gaseous conduction 20 between the electrodes in one direction, said cathode being hollow and so related to the anode that electrons may travel from the interior thereof along paths longer than 25 said length.

15. A rectifier comprising a cathode and an anode, means for restricting conduction between the electrodes comprising a gas space comparable to the mean free path of 30 electrons in the gas, means for increasing the permissible pressure in said space comprising inert monatomic gas, and means comprising differently shaped electrode surfaces permitting gaseous conduction between 35 the electrodes in one direction, said cathode being hollow and so related to the anode that electrons may travel from the interior thereof along paths longer than the shortest 40 distance between the electrodes.

16. In electrical apparatus having electrodes separated by a gas space comparable in length to the mean free path of electrons in the gas for restricting gaseous conduction between the electrodes, the method 45 which comprises increasing the permissible gas pressure in the space over that pressure of air, in a space of the same length, which affords corresponding restriction of gaseous conduction, by using monatomic gas in the 50 space.

17. The method of controlling conduction between electrical discharge electrodes which comprises restricting conduction between the electrodes by a gas space comparable to the 55 mean free path of electrons in the gas, increasing the permissible gas pressure in the space by using monatomic gas in said space, and producing conduction between the electrodes in one direction by causing the electrons from one electrode to travel in paths 60 longer than the shortest distance between the electrodes.

18. The method of controlling conduction between electrical discharge electrodes which 65 comprises restricting bi-lateral conduction

between the electrodes by a gas space less than the mean free path of electrons in the gas, increasing the permissible separation of the electrodes by using monatomic gas in said space, and producing unilateral conduction 70 between the electrodes by causing the electrons from one electrode to travel in paths longer than the shortest distance between the electrodes.

19. In electrical apparatus of the type 75 having juxtaposed surfaces spaced sufficiently close together to prevent initiation of substantial conduction directly across the space by normal potential differences, the method of increasing the insulating effect 80 of the space which comprises substituting, in lieu of some of the air in the space, a gas having a longer ionizing mean free path.

20. Electrical apparatus of the type having 85 opposed surfaces separated by a space sufficiently short to prevent initiation of substantial conduction directly across the space by potentials high enough to initiate conduction across longer gaps, characterized by means for increasing the permissible 90 length of said space over the length in air at the same pressure for a corresponding degree of restriction of gaseous conduction, said means comprising monatomic gas in 95 said space.

21. Electrical apparatus of the type having 100 opposed surfaces separated by a gas space sufficiently short to prevent initiation of substantial conduction directly across the space by potentials high enough to initiate 105 conduction across longer gaps, characterized in that the gas in said space has an ionizing mean free path sufficiently long, compared with that of air, to permit a gas pressure many times as high as the maximum air pressure which would inhibit conduction.

22. Electrical apparatus of the type having 110 opposed surfaces separated by a space sufficiently short to prevent initiation of substantial conduction directly across the space by potentials high enough to initiate conduction across longer gaps, characterized by means for increasing the permissible 115 length of said space over the length in air at the same pressure for a corresponding degree of restriction of gaseous conduction, said means comprising gas in said space having a relatively long ionizing mean free path compared with air.

23. A gaseous conduction rectifier employing 120 an arrangement of electrodes in which the cathode functions below the temperature at which the operation is dependent upon thermionic emission from the cathode, and containing monatomic gas at a pressure at least of the order of magnitude of one-half centimeter.

CHARLES G. SMITH,
